UNITED STATES PATENT OFFICE.

SAMUEL SEGAL, OF NEW YORK, N. Y.

KEY-DUPLICATING MACHINE.

1,335,351.

Specification of Letters Patent. Patented Mar. 30, 1920.

Application filed May 20, 1919. Serial No. 298,372.

To all whom it may concern:

Be it known that I, SAMUEL SEGAL, a citizen of the United States, and a resident of New York, in the county of New York and State of New York, have invented certain new and useful Improvements in Key-Duplicating Machines, of which the following is a specification.

My invention relates to key-duplicating machines and has for its object the production of a machine of extreme simplicity of construction which shall be adapted to duplicate keys for cylinder locks, as the well-known Yale keys, as well as to duplicate keys having rectangular teeth on the biting edge thereof or what is known as "flat" keys.

Other and further objects of the invention will appear from the following description, the invention consisting in the novel parts and combinations of parts hereinafter more particularly described and then specified in the claims.

In the accompanying drawings:

25 Fig. 1 is a plan view of my improved key-duplicating machine showing the carriage with its work-holding clamps swung up manually in position to duplicate a key for cylinder locks.

30 Fig. 2 is a vertical cross-section on the line 2—2 of Fig. 1.

Fig. 3 is a front elevation of my improved machine.

35 Fig. 4 is a plan view of my improved machine showing the carriage and work-holding clamps in the proper position for duplicating a "flat" key.

Referring more particularly to the several figures of the drawing:

40 10 indicates the base of my improved machine which is provided with a body portion 11 having side plates 12 carrying the rod 13 connecting said side plates together.

45 14 indicates the carriage of the machine which is horizontally slidably mounted on the rod 13. Said carriage is provided with the arms 15 extending outwardly therefrom and with one-piece work-holding clamps 16 and 16' preferably integral with said arms. The said work-holding clamps are ring-shaped and have enlarged heads with slots 17 cut therethrough forming two flat opposed surfaces or jaws adapted to hold therebetween a key in clamped position. Each of said work-holding clamps is also provided with a shoulder or flange 18

formed on one of the opposed faces of the slot 17 and with a hook or latch 19 pivoted to the head of the clamp. 20 indicates suitable screw-threaded bolts extending through the clamps 16 and 16' and which are adapted to be operated by the winged nuts 21 to draw the flat opposed surfaces or jaws of the slotted heads together when the nuts are turned in one direction or to allow them to move away from each other due to the spring action in the metal of the clamps, when the nuts are turned in the other direction, in an obvious manner.

50 The work-holding clamps 16 and 16' are identical in size and construction, the said clamp 16 being adapted to hold and clamp a master key 22 between the jaws thereof and the clamp 16' a key blank 22' to be duplicated and as illustrated. The keys are properly positioned in their respective clamps by seating the back edges thereof on the shoulders or flanges 18 of the clamps so that the biting edges of the keys extend outwardly from the clamps, the proper horizontal positions of the keys in their respective clamps being determined by engagement of the shoulders 23, 23' of the keys with the flat sides of the pivoted hooks or latches 19.

55 24 indicates a guiding finger suitably mounted in a post 25 extending upwardly from the body of the machine and held in said post by pins 26 or other suitable means. The outer edge of said guiding finger is beveled as illustrated and is adapted to engage the notches in the biting edge of a cylinder lock key. 27 indicates a guiding finger mounted in a post 28 similar in construction to the post 25. The said guiding finger 27 is held in mounted position by suitable 60 pins 26' as shown and the outer edge of the finger is flat or squared and is adapted to engage or fit within the indentations intermediate the rectangular teeth of a "flat" key, as for instance the indentations 29 of 65 the key 30 shown in Fig. 4, the key blank 30' being adapted to have similar indentations cut therein as will be described.

70 31 indicates a double standard extending upwardly from the machine having a shaft 32 journaled therein and held at one end by a suitable nut 33 and at the other end by a driving wheel 34 which is provided with a handle 35 so as to rotate the said shaft 32. 36 is a rotary cutting tool mounted on the 75 shaft 32 and having a beveled edge similar in configuration to the outer beveled edge

- of the guiding finger 24. 37 indicates a rotary cutting tool of a width equal to the width of the guiding finger 27 and provided with a "saw-tooth" edge as illustrated.
- 5 The distances between the centers of the clamps 16, 16', the guiding finger 24 and rotary cutting tool 36 and the guiding finger 27 and rotary cutting tool 37 are equal. Moreover, the outer edges or the edges 10 nearest the clamps of the guiding fingers 24 and 27 and the rotary cutting tools 36 and 37 lie in the same horizontal plane.

The duplicating operation is as follows: Assuming a key for a cylinder lock is to 15 be duplicated, the master key is properly positioned in clamp 16 and the key blank in clamp 16' as shown in Fig. 3 and as has been explained. The wheel 34 is then operated to rotate the cutting tool 36 and the carriage 20 is swung up manually on the rod 13 (see Fig. 1) to cause either end of the biting edge of the master key to be pressed against the guiding finger 24. The carriage is moved slowly and horizontally along the 25 rod 13, contact at all times being preferably kept between the biting edge of the master key and the guiding finger 24. The forward movement of the carriage toward the guiding finger is limited by the depth of 30 each notch or cut in the biting edge of the master key and a notch or cut of equal depth will be made in the edge on the key blank by the cutting tool 36 as is obvious.

In duplicating a flat key, the carriage is 35 swung to the left on rod 13 until clamp 16 is in vertical alinement with the guiding finger 27 and clamp 16' with the rotary cutter 37 (see Fig. 4). The master key and key blank are properly positioned in their 40 respective clamps and by rotation of shaft 32 and successive engagement of the guiding finger 27 with each indentation 29 of the master key, similar indentations are cut in the biting edge of the key blank 30', as will 45 be manifest, by the cutting tool 37.

What I claim as my invention is:—

1. In a key-duplicating machine, a pair of work-holding clamps for holding and clamping a master key and key blank, a guiding finger and a cutting tool adapted to coöperate respectively with said work-holding clamps and a second guiding finger and cutting tool adapted to also coöperate respectively with said work-holding clamps.

55 2. In a key-duplicating machine, a carriage, a pair of work-holding clamps secured to said carriage and adapted to hold and clamp a master key and key blank, a guiding finger adapted to engage the notches 60 in the biting edge of a key of the cylinder lock type when said key is held in one of said work-holding clamps, a cutting tool adapted to duplicate from a key blank held in the other clamp the master key of the 65 cylinder lock type, a second guiding finger

adapted to engage the teeth of a "flat" master key when said key is held in one of said work-holding clamps and a second cutting tool adapted to duplicate from a key blank held in the other clamp the "flat" master 70 key.

3. In a key-duplicating machine, a horizontally slideable carriage mounted on said machine, a pair of work-holding clamps secured to said carriage and adapted to hold and clamp a master key and key blank, a pair of guiding fingers extending from the machine, and a pair of cutting tools mounted on the machine, the first of said guiding fingers and said cutting tools or the second 80 of said guiding fingers and said cutting tools being adapted to engage a master key and key blank held by said work-holding clamps.

4. In a key-duplicating machine, a carriage 85 mounted on said machine and adapted to be moved horizontally thereof, a pair of work-holding clamps secured to said carriage and adapted to hold and clamp a master key and key blank, a pair of guiding fingers independently mounted on the machine, a shaft journaled in a suitable standard and a pair of rotary cutting tools mounted on said shaft.

5. In a key-duplicating machine, a carriage 95 mounted on said machine and adapted to slide horizontally thereof, a pair of work-holding clamps secured to said carriage and adapted to hold and clamp a master key and key blank, a pair of guiding fingers 100 independently mounted on the machine, adapted to engage the biting edge of the master key and a pair of cutting tools adapted to engage and cut the biting edge of the key blank to duplicate the master key, the distances between the centers of the 105 clamps, the first guiding finger and first cutting tool and the second guiding finger and second cutting tool being substantially equal.

6. In a key-duplicating machine, a carriage 110 mounted on said machine, a pair of work-holding clamps secured to said carriage and adapted to hold a master key and key blank, a pair of guiding fingers independently mounted on the machine and 115 adapted to engage the biting edge of the master key, a shaft journaled in a suitable standard and a pair of cutting tools mounted on said shaft and adapted to engage the biting edge of the key blank.

7. In a key-duplicating machine, a carriage 120 mounted on said machine, a pair of work-holding clamps secured to said carriage and adapted to hold a master key and key blank, a guiding finger having a beveled edge adapted to engage the notches in the biting edge of a master key when held in its clamp, a cutting tool having a beveled edge adapted to duplicate the notches of the master key in the biting edge of a key blank.

when held in its clamp and when the guiding finger engages the biting edge of the master key, a second guiding finger having a flat edge adapted to engage the teeth of a master key when held in its clamp and a second cutting tool having a saw-tooth edge adapted to duplicate the teeth of the master key in the biting edge of a key blank when held in its clamp and when the guiding finger with the flat edge engages the teeth of the master key.

5

Signed at New York, in the county of New York and State of New York, this 17th day of May, A. D. 1919.

SAMUEL SEGAL.
